UNITED STATES PATENT OFFICE

WALDEMAR L. LINDGREN, OF WAUKEGAN, ILLINOIS, ASSIGNOR OF ONE-HALF TO JOHN E. ERICSSON, OF CHICAGO, ILLINOIS

DISHWASHING MACHINE

Application filed May 2, 1929. Serial No. 359,916.

My invention is concerned with dish washing machines of the type in which the dishes, etc., are carried through the machine on the upper run of an endless carrier, such, for instance, as is shown in my application No. 317,176, filed November 5, 1928, and my present invention is designed to produce such a device, in which knives, forks, spoons, etc., may be readily carried through it, and, when desired, be discharged into a special receptacle designed to receive them, instead of being discharged on the table on which cups, saucers, plates, etc., are discharged.

To this end, it consists in a novel structure and combination of elements, all of which will be hereinafter fully described, and the novel features and combinations particularly pointed out in the claims.

To illustrate my invention, I annex hereto two sheets of drawings, in which the same reference characters are used to designate identical parts in all the figures, of which,—

Fig. 1 is mainly a central longitudinal, vertical section through a dish-washer embodying my invention;

Fig. 2 is a top plan view of the same as seen in section on the line 2—2 of Fig. 1; and

Figs. 3 and 4 are enlarged details in side elevation, as seen from the lines 3—4 of Fig. 2.

In machines of this type, which are usually adapted to be placed upon the bottom of a sink 10, I preferably employ the skeleton framework composed of two side pieces 11 having the legs 12 supporting the machine, and provided with the receiving and discharge tables 13 and 14, which preferably consist of the horizontal web with the downwardly projecting triangular portion 15 at each end, which triangular portions are connected by the horizontal bars 16, which are secured on the ends of abutments provided therefor on the frame by the screws 17.

These bars 16 serve as a partial means for securing the two sections together, their action being supplemented by that of the pair of shafts 18 and 19 journaled in suitable bearings in the side frames and having the sprocket wheels 20 and 21 secured thereon just inside of the side frames. These sprocket wheels 20 and 21 co-operate with the ends of

the transverse rods 22, which are connected at their ends by the links 23 which form a pair of chains, with the ends of the rods constituting the pivotal connections therefor. As these rods are separated some little distance and it is desired to carry such articles as knives, forks and spoons on the surface of the carrier thus formed, the rods 23 are further connected, as by the wires 24, which extend entirely around the carrier and are held in place by being given a turn around each of the rods, the turns or coils being placed in the annular grooves 25 formed in the rods for this purpose. Suitable power, such as that of an electric motor 26, is applied to the carrier through the medium of a worm 27 on the armature shaft meshing with a worm gear 28 on the horizontal shaft 29 having a worm 30 on its other end meshing with a worm gear 31 secured on the shaft 18.

The carrier thus far described is preferably removable from the sink, and, to furnish the necessary hot suds for washing the dishes, I provide the perforated pipes 32 and 33 extending in use transversely across the carrier above and below the upper run, so that water delivered from the hot-water faucet 34 through the piping indicated in dotted lines in Fig. 1 will be sprayed upward from the pipe 32 on the bottom of the dishes and downward from the pipe 33 on the top as they move slowly between the pipes by the movement of the carrier. The pipes 32 and 33 are provided with the soap boxes 35 and are preferably pivoted to the connecting pipes at 36 so that they can be swung to one side and parallel to the rear wall of the sink 10 when the washing-machine is not in use. Similar spray pipes 37 and 38 are provided at the other end of the machine and connected to the faucet 34, and spray the dishes with clear rinse water before they leave the machine.

The structure thus far described is that shown in my aforesaid application Serial No. 317,176, filed November 5, 1928.

Where a considerable number of knives, forks, spoons, etc., are placed on the carrier to be washed, it is desirable to provide means whereby they can be discharged into a receptacle automatically, and for this purpose I

secure on the cross piece 16 at the discharge end the trough 39, which is preferably composed of sheet metal, and the body portion of which is preferably semicylindrical in its outline.

At the edge above the cross piece 16, I preferably bend over the portion 40 so that it comes substantially in contact with the carrier as it passes beneath it. Obviously, knives, forks, spoons, etc., which are laid lengthwise of the carrier, will drop off of the carrier on to the inclined portion 40, and thence fall into the receptacle 39, whence they can be removed at leisure.

15 I have found that sometimes portions of the forks and spoons, especially, project through the interstices between the rods 22, and make trouble in discharging. To prevent this possibility, I provide the cam plate 41, which is preferably composed of sheet metal and is of the design seen in Figs. 1 and 2, where it will be seen that the downwardly-turned ends of the ears 42 are secured by screws 43 to the inner wall of the side pieces or frames 11. 20 The main body of the plate 41 is rectangular in its outline, and slants upwardly, as seen in Fig. 1, until it is directly beneath the carrier, where it is then curved to form the portion 44, which extends as a portion of a cylinder directly beneath the carrier. If any portion of the cutlery projects through the belt, as it reaches and passes over the plate 41, it will be cammed upward and outward, so that there is no possibility of its failing to drop off of the carrier when it reaches the portion 40.

When the apparatus is thus used for washing knives, forks, spoons, etc., it is necessary that a considerable space exist between the discharge table 14 and the nearest portion of the carrier that is in the same horizontal plane; but when the apparatus is to be used in washing plates, saucers, cups, etc., such space is objectionable, as it is desired that the articles thus being washed should pass automatically from the belt on to the table 14. To bridge this necessary gap at such times, I employ the bridge plate 45, which preferably consists of sheet metal, and has the ears 46 struck up from the ends of the plate in position to rest on the upper edges of the side frames 11, as clearly shown in Figs. 2 and 3. The plate 45 is supported by the wire bail 47, which has its inwardly turned ends 50 48 extending through suitable apertures provided in the brackets 15 at that end. The outer edge 49 of the bridge plate 45 is curved about and secured to the body of the bail 47 in the manner clearly shown in Figs. 3 and 4. 55 When the bridge plate 45 is in use, it occupies the position shown best in Figs. 2 and 3, and when not in use, it is turned back to the position shown in Fig. 4, where the knives, forks, etc., are free to drop down into the receptacle 39. The table 14 preferably

has the recess 50 therein at its central portion, which is convenient for taking hold of the plates and saucers as they are delivered thereon.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. In a dish-washing machine, the combination with a horizontally-movable skeleton carrier consisting of a pair of endless chains mounted on wheels and connected by parallel transverse rods in turn connected by longitudinal wires, of means for rotating said wheels, and a cam plate beneath the same extending between the wheels over which the cutlery is discharged, and in substantial contact with the rods at the discharge point.

2. In a dish-washing machine, the combination with a frame consisting of a pair of side plates, of a horizontally-movable skeleton carrier consisting of a pair of endless chains mounted on wheels journaled in said side frames and connected by transverse parallel rods in turn connected by wires, means for rotating said wheels to move the carrier, and a cam plate beneath said carrier secured at its lower end to the inner side of the side plates and having the main portion thereof extending upwardly at an angle to a point directly beneath the carrier and thence curved concentric with the axes of the wheels at the discharge end to the discharge point.

3. In a dish-washing machine, the combination with side frames, of a horizontally-movable skeleton carrier adapted to carry table cutlery thereon by the supporting action of the carrier alone, and a receptacle secured to said frame at the discharge point of the carrier, into which receptacle the cutlery is dropped.

4. In a dish-washing machine, the combination with side frames, of a horizontally-movable skeleton carrier adapted to carry table cutlery thereon by the supporting action of the carrier alone, a receptacle secured to said frame at the discharge point of the carrier, into which receptacle the cutlery is dropped, a discharge table above said receptacle, and a switch plate pivoted adjacent the table to direct the cutlery on to the table or allow it to fall into the receptacle, depending on how it is adjusted.

5. In a dish-washing machine, the combination with a frame, of a horizontally-movable skeleton carrier mounted therein adapted to carry table cutlery thereon by the supporting action of the carrier alone,

means for moving said carrier, a cam plate beneath the same near the point of discharge adapted to raise any cutlery thereon extending through the carrier, and a receptacle secured to said frame at the discharge point of the carrier, into which the cutlery is dropped.

6. In a dish-washing machine, the combination with a frame, of a horizontally-movable skeleton carrier mounted therein adapted to carry table cutlery thereon, means for moving said carrier, a cam plate beneath the same near the point of discharge adapted to raise any cutlery thereon extending through the carrier, a receptacle secured to said frame at the discharge point of the carrier, into which the cutlery is dropped, a discharge table carried by said frame above said receptacle, and a switch plate pivoted on the frame adjacent the table to direct the cutlery on the table or allow it to fall into the receptacle, depending on how it is adjusted.

7. In a dish-washing machine, the combination with a frame consisting of a pair of side plates, of a horizontally-movable skeleton carrier consisting of a pair of endless chains mounted on wheels journaled in said side frames and connected by transverse parallel rods in turn connected by wires, means for rotating said wheels to move the carrier, a cam plate beneath said carrier secured at its lower end to the inner side of the side plates and having the main portion thereof extending upwardly at an angle to a point directly beneath the carrier and thence curved concentric with the axes of the wheels at the discharge end to the discharge point, a cross piece connecting the ends of the frame in the plane of the hubs of the wheels, and a sheet-metal trough secured at one side thereof to said cross piece.

8. In a dish-washing machine, the combination with side frames, of a horizontally-movable skeleton carrier adapted to carry table cutlery thereon, a receptacle secured to said frames at the discharge point of the carrier, into which receptacle the cutlery is dropped, a discharged table above said receptacle, and a switch plate pivoted adjacent the table to direct the cutlery on to the table or allow it to fall into the receptacle, depending on how it is adjusted, said switch plate consisting of a sheet-metal plate supported by a wire bail having its inturned ends engaging the supporting brackets of the table.

In witness whereof, I have hereunto set my hand this 12th day of April, 1929.

WALDEMAR L. LINDGREN.
